UNITED STATES PATENT OFFICE.

ARTHUR DUFault, OF PROVIDENCE, RHODE ISLAND.

DESIGN FOR A RAZOR-HOLDER.

SPECIFICATION forming part of Design No. 22,831, dated October 10, 1893.

Application filed June 26, 1893. Serial No. 478,896. Term of patent 7 years.

To all whom it may concern:

Be it known that I, ARTHUR DUFault, a subject of the Queen of Great Britain, residing at Providence, in the State of Rhode Island, 5 have invented and produced a new and original Design for Razor-Holders, of which the following is a specification, reference being had to the accompanying drawings, forming a part thereof.

Figure 1, represents a top view of the razor holder, and Fig. 2, is a side view thereof.

In the drawings, A represents a razor holder

circular in form, and provided with the holes b, b, and my new and original design for such a razor holder, consists in the convex head c, 15 the circular base d, and the circular neck f, which connects the base d to the head c.

What I claim is—

The design for a razor holder, herein shown and described.

ARTHUR DUFault.
